UNITED STATES PATENT OFFICE.

WILLIAM BARR, JR., AND DAVID MCKAY, OF KIRKCUDBRIGHT, SCOTLAND.

METHOD OF FORMING TUBULAR PLAQUETS OF INDIA-RUBBER, &c.

SPECIFICATION forming part of Letters Patent No. 519,900, dated May 15, 1894.

Application filed October 31, 1893. Serial No. 489,601. (No specimens.) Patented in England May 31, 1892, No. 10,344; in France March 27, 1893, No. 228,923, and in Germany March 30, 1893.

To all whom it may concern:

Be it known that we, WILLIAM BARR, Jr., and DAVID MCKAY, subjects of the Queen of Great Britain and Ireland, residing at Kirkcudbright, Kirkcudbrightshire, Scotland, have invented an Improved Method of Forming Tubular Plaques and other Tubular Articles of India-Rubber, Ebonite, and the Like, (for which we have obtained Letters Patent in Great Britain, No. 10,344, dated May 31, 1892; in France, No. 228,923, dated March 27, 1893, and in Germany, dated March 30, 1893,) of which the following is a specification.

Our invention has reference to and comprises an improved method of forming tubular plaques, and other tubular articles, but especially suitable for forming tubular plaques of vulcanized dental rubber for use on the nose frames of eye glasses, also applicable however for forming other tubular articles, especially those of short length, of small diameter and made of dental rubber, ebonite, and the like, and of square, flat, round, oval, fluted, polygonal and other shapes. The improvements consist, first, and essentially in the use of brass, copper, German silver, iron, and other wire of smooth surface and suitable temper for a central core, that is, metal which is capable of being annealed until soft enough to stretch without breaking, before being covered with the material which is to form the tubular article, and of being withdrawn by a process of drawing and lengthening said soft metal core in a stretching machine after formation and vulcanization of the tubular article thereon anyhow so that it will become contracted and easily withdrawn from the article, and leave the latter free in its finished state. In carrying our improved method into practice we use a mold tool formed with a series of U shaped channels in which the plaque material and central cores are embedded; the product being subsequently vulcanized, and the central cores withdrawn.

In order to enable others skilled in the art to which our invention relates to understand how it may be carried into practice, we have hereunto appended an explanatory sheet of drawings in which the same reference letters

are used to indicate corresponding parts in all the figures where shown.

Figure 1 is an end elevation partly in section of the mold tool used for forming the tubular articles. Fig. 2 is a plan view of 55 same partly in section, and Fig. 3 is a corresponding edge elevation. Fig. 4 is an end view partly in section of the flask tool used in vulcanizing the tubular articles during their process of manufacture. Fig. 5 is a 60 plan view of one of the upper frames, and Fig. 6 a corresponding view of the base plate; while Fig. 7 is a corresponding edge elevation of this tool. Figs. 8 and 9 are an inverted plan view, and end section showing 65 three tubular plaque articles with their metal cores as formed in one piece after coming out of the tool shown in Figs. 1 to 3; and Figs. 10 and 11 are a plan view and end section respectively of a tubular plaque article 70 complete after vulcanization and removal of the internal metal core.

Referring to the drawings:—The tool shown in Figs. 1 to 3 consists of a base plate A formed with a series of longitudinal vertical 75 ribs a with U shaped channels a² between these and a series of vertical projections a' at the two ends of these vertical ribs a the base plate A being covered over with a top plate A' with center wings A² after the wires 80 and sheets of rubber have been inserted.

The tool shown in Figs. 4 to 7 consists of four movable parts a lower and upper plate B and B' and two intermediate rectangular open frames B² B³ the upper of these B³ shown 85 detached in Fig. 5, being formed with a series of notched grooves b to receive the ends of the metal cores in the tubular plaques.

To manufacture the tubular plaques we proceed as follows:—Taking the tool shown 90 in Figs. 1 to 3 having a series of U shaped channels a², we dust it over with French chalk carefully blowing out all that may be lying loose; we do the same with the inside of the lid. We then lay a sheet of dental 95 rubber over channels a². Over this, and in each channel, we place one of our annealed metal cores c, and, over these again, a sheet of dental rubber. Taking lid A' we place it on, and then apply pressure such pressure as 100

- is obtainable from an ordinary letter press or other similar device. We however do not press the rubber to its bed at one pressing. It may take a few pressings to get it there 5 and before a proper impression of letters at the bottom of channel a^2 is obtained. Between each pressing we use a slight dusting of French chalk on the tool. This prevents sticking. Having got the impression of our 10 molds (which is the same as saying "having got our plaques molded into shape") they are ready for vulcanizing. This is done in exactly the same way as dentists vulcanize their work, namely, as surrounded with plaster of paris in molds and under pressure. Our practice may be best explained by the tool formed of four brass pieces, shown in Figs. 4 to 7. These brass pieces when put together, as shown in Fig. 4 constitute a flask. 15 20 They are made up of two lids, and two rectangular open frames $B^2 B^3$ just under one-fourth of an inch deep. Into this flask we put our sheet of unvulcanized plaques surrounded with plaster of paris. Before the plaster of paris sets they are subjected to pressure in an ordinary cramp and allowed to harden before vulcanization. Vulcanization must be performed under pressure. When more than one flask containing plaques are to be vulcanized they may be placed on top of each 25 30 other in a cramp sufficiently large to include them all and keep all under pressure.
- We fill our flasks with plaster of paris and unvulcanized plaques as follows:—The process is simple. Taking a flat marble slab, about a foot square, place the half of flask thereon (half of flask consists of one of the lids $B B'$ and one of the rectangular squares $B^2 B^3$). Into this pour a mixture of plaster of 35 40 paris and water, such mixture to be as thick as say good cream, and before it has had time to set, also place in the flask, face downward and in plaster of paris the sheet of plaques to be vulcanized taking good care to work the

same backward and forward in the plaster of paris to well coat them with it. Indeed a good plan is to give the sheet of unvulcanized plaques a few rapid dips in the plaster of paris solution before putting them in the flask. This done the other rectangular frame 50 is placed in position (that is one on top of its neighbor). Plaster of paris mixture is poured into this sufficient to well fill it. The lid is now put on and the cramp (as described for applying pressure to single flasks of plaques) 55 brought into use. Flasks thus pressed and allowed to harden or set may lie aside until other similar flasks are ready, when all may be vulcanized together in an exactly similar cramp but large enough to contain them. It 60 will be seen from what we have described, that the plaques to be vulcanized are in the center of their plaster of paris surroundings. Plaques being cut up into lengths having a central wire or core in each, the free ends 65 of said soft metallic central cores are placed in a wire stretching machine, and after stretching the cores a little they can be readily withdrawn, so leaving the tubular plaque articles free as seen in Figs. 10 and 11. 70

What we claim is—

A method of forming tubular plaques and other tubular articles of dental rubber, ebonite and the like, consisting in surrounding an annealed metal core with the dental rubber 75 or the like, then vulcanizing the rubber, and stretching the said annealed core whereby the core is contracted in diameter, and then withdrawing the core, substantially as and for the purpose set forth. 80

In testimony whereof we have signed our names to this specification in the presence of two subscribing witnesses.
